[57] CLAIM

The ornamental design of the golf bag top with putter well, as shown and described.

DESCRIPTION

FIG. 1 is perspective view of a golf bag top with putter well showing our new design;

FIG. 2 is an enlarged scale perspective view thereof;

FIG. 3 is a right side view thereof;

FIG. 4 is a top plan view thereof;

FIG. 5 is a left side view thereof;

FIG. 6 is a rear view thereof;

FIG. 7 is a front view thereof; and,

FIG. 8 is a bottom view thereof.

The broken line showing of a golf bag is for illustrative purpose and forms no part of the claim.
